UNITED STATES PATENT OFFICE.

EMERY C. HODGES, OF FARMER CITY, ILLINOIS.

DESIGN FOR A TOMBSTONE OR MONUMENT.

SPECIFICATION forming part of Design No. 34,743, dated July 2, 1901.

Application filed May 10, 1900. Serial No. 16,237. Term of patent 7 years.

To all whom it may concern:

Be it known that I, EMERY C. HODGES, a citizen of the United States, residing at Farmer City, in the county of DeWitt and State 5 of Illinois, have invented and produced a new and original Design for a Tombstone or Monument, of which the following is a specification.

My invention is a new and useful design 10 for a tombstone or monument, the object being the provision of a design of this character and for this purpose which will combine the requisites of usefulness and beauty, as well as be symbolic of the fact that our Savior is 15 the tree and the people its branches.

To attain the desired objects, my invention consists of the design for a tombstone, as shown and described herein.

The figure of the drawing represents a front 20 view of my complete design, showing the combined features in their proper and relative positions.

A is my tombstone or monument, which represents the stump of a tree, having thereon the panel B for a suitable inscription and provided with the lily ornamentation C at the base, the oak-leaf and acorn ornamentation D, and the grape-vine with grapes E, the said ornamentation being arranged to give the most attractive effect. Near the base of the 25 tree-stump is also the bird ornamentation F, at one side near the top the squirrel G, and at the top is the cross with wreath of flowers H.

I claim—

The design for a tombstone or monument 30 herein shown and described.

In testimony whereof I affix my signature in presence of two witnesses.

EMERY C. HODGES.
